PULL FOR DOORS, DRAWERS AND THE LIKE

Don Heyer, El Monte, Calif., assignor to M and H Industries, Inc., Los Angeles, Calif., a corporation of California

Application November 28, 1958, Serial No. 53,558

Term of patent 14 years

(Cl. D50—3)

Fig. 1 is a perspective view of a pull for doors, drawers and the like showing my new design;

Fig. 2 is a sectional view thereof as taken on the line 2—2 of Fig. 3;

Fig. 3 is a front elevation thereof;

Fig. 4 is a side elevation thereof; and

Fig. 5 is a rear elevation thereof.

I claim:

The ornamental design for a pull for doors, drawers and the like, as shown.
